(57) **CLAIM**

The ornamental design for a soft storage case with stacked pockets for disc and cover, as shown and described.

DESCRIPTION

FIG. 1 is a perspective view of a soft storage case with stacked double dip pockets for holding discs, such as CDR or DVD, in inner pockets and a cover in outer transparent pockets;

FIG. 2 is a front view thereof, showing the transparent pockets;

FIG. 3 is a back view thereof, showing the transparent pockets;

FIG. 4 is a left side view thereof;

FIG. 5 is a right side view thereof;

FIG. 6 is a top view thereof; and,

FIG. 7 is a bottom view thereof.

The broken lines shown throughout the figures, are understood to represent seams.
